ELEVATOR CONTROL SYSTEM

William F. Eames, Edgewood, Pa., assignor to
Westinghouse Electric & Manufacturing Com-
pany, a corporation of Pennsylvania

Application October 11, 1929. Serial No. 398,941

12 Claims. (Cl. 187—29)

My invention relates to control systems for elevators and more particularly to control systems in which the elevator cars are started by car switches and are stopped by the operation 5 of push buttons in the cars or at the landings.

One object of my invention is to provide for 10 maintaining a control push button in its depressed position, after it has been operated, until a car has started to answer the call, to thereby indicate that the button has been depressed to make the car stop.

Another object of my invention is to provide 15 an elevator-control system in which the push buttons shall be maintained in a set condition after they are depressed, so that passengers at the floor landings or the operator in the car may simply press a button to cause the car to stop at a desired landing and then the stop call will be automatically registered or maintained after 20 pressure is removed from the button until the call is answered.

A further object of my invention is to provide 25 a fully-selective elevator-control system; that is, a system in which a registered call will be cancelled the instant that a car starts to answer the call, in order to prevent any following cars from being affected by the same call.

Another object of my invention is to provide 30 for reducing the wiring and the number of pieces of apparatus that are usually required in elevator-control systems of the above-designated character.

It is also an object of my invention to provide 35 an elevator-control system in which the car may be operated at express speed but will be automatically reduced from its express speed to its normal working speed as it approaches a landing for which a stop call has been registered, so that it may arrive within the stopping zone at such 40 speed as to come to rest exactly level with the floor landing.

Other objects of the invention will, in part, be 45 obvious and will, in part, appear hereinafter.

For a complete understanding of the invention, 50 reference may be had to the following description, taken in connection with the accompanying drawings, in which:

Figures 1, 2, 3 and 4 collectively constitute a 55 diagrammatic representation of the control circuits and apparatus embodying my invention, as applied to an elevator system.

The drawings illustrate a pair of elevator cars 60 A and B as suitably suspended by cables Ca and Ca' which pass over the hoisting drums D and D'

to suitable counterweights CW and CW', respectively.

Inasmuch as the control systems for the cars A and B are alike, only the control system for car A will be described.

The hoisting drum D for the car A is directly coupled to an armature EM' of an elevator motor EM, the field winding EMF of which is connected, for constant-voltage energization, to a source of power designated as the supply conductors L1 and L2.

A variable-voltage system of control may be provided for operating the hoisting motor EM wherein the armature EM' is connected in loop circuit with the armature G' of a generator G. The generator G is provided with a separately excited field winding GF and a cumulative series field winding GSF.

The armature G' of the generator G is suitably driven by means of a driving motor M illustrated as being of the shunt-wound type having its armature M' and its field winding MF connected in shunt relation to the supply conductors L1 and L2.

The direction and speed of the hoisting motor 80 EM may be suitably controlled by controlling the direction and value of the excitation current that is supplied to the separately excited field winding GF of the generator G.

The direction of the excitation current for the 85 field winding GF may be suitably controlled by means of an up-direction switch 1 and a down-direction switch 2, while the value of the current supplied to the field winding may be controlled by means of an intermediate-speed 90 relay 3, a normal or high-speed relay 4 and an express relay 5.

The operation of the up-direction and down-direction switches 1 and 2, as well as the intermediate-speed relay 3 and the normal high-speed relay 4 may be controlled by means of a car switch CSA that is mounted upon the car A in position to be actuated by an attendant thereon.

An express-speed switch 9 is provided for controlling the express-speed relay 5. The switch 9 may be disposed at any suitable point where a "dispatcher" in charge of the elevators may close the switch to speed up the operation of the car A at any time desired. For instance, if the high speed, that is, the normal working speed of the car, is, say, 700 feet per minute the "dispatcher" may cause it to operate at an express speed of, say, 800 feet per minute.

A relay 6 is connected in the elevator control 110

system in such manner that it will deenergize the express-speed relay 5 to decelerate the car from express speed to high speed; that is, its normal working speed, when the car nears a landing at which it will be stopped by a registered call.

A relay 7 is connected across the loop circuit of the motor EM and is provided with contact members that open or close gaps in the energized circuits for the high-speed relay 4 and the express-speed relay 5, in accordance with the voltage of the generator G, thereby delaying the energization of the relays 4 and 5 until the generator voltage reaches a predetermined value and thus preventing the car from being operated in a jerky manner.

Any suitable means may be employed which will, when energized, automatically stop the car A level with the floors past which it moves. In the present instance, I have illustrated the stopping means as including an automatic inductor landing system, such as is disclosed in the pending application of E. M. Bouton, Serial No. 731,921, filed August 14, 1924 and assigned to 25 the Westinghouse Electric & Manufacturing Company.

The inductor landing system for the car A includes an up-high-speed inductor relay HU, and up-intermediate-speed inductor relay SU 30 and a stopping inductor relay S for causing the car to be automatically decelerated from its high and intermediate speeds, respectively, and brought to a stop at an exact level with a floor when the car is travelling upwardly. Similarly, 35 down-high-speed inductor relay HD, a down-intermediate-speed inductor relay SD and the stopping inductor relay S will cause the car to slow down and stop at the floors when it is travelling downwardly.

40 It is assumed that each of the floors past which the car A moves will be provided with a set of inductor plates that will cooperate with the inductor relays as the car approaches predetermined points in advance of the floor at which a stop is to be made to effect the operation of the relays.

The inductor plates associated with any one floor for the car A are illustrated as comprising an up-high-speed inductor plate HU', an up-intermediate-speed inductor plate SU' and a stopping inductor plate S' for successively operating the up-inductor relays HU, SU and S as the car makes an up stop. When the car is travelling downwardly, a high-speed inductor plate 55 HD', an intermediate-speed inductor plate SD' and a stopping inductor plate S' will successively operate the inductor relays HD, SD and S, respectively, as the car approaches a down stop.

In the elevator system illustrated in the drawings, the energization of the inductor relays on each car for stopping that car is effected by a control relay that is operated by a plurality of associated floor relays. Thus, the stopping of the car may be controlled by the floor relays. The floor relays, in turn, are controlled by push buttons in the cars and at the floor landings. With this arrangement of apparatus, the operation of a push button at a floor landing will cause a car running in a corresponding direction to stop at that landing, while the operation of a push button in a car will cause that car to stop at the landing represented by that push button.

Inasmuch as the present system is of the high-speed type in which the normal slow-down dis-

tance of the cars is greater than the distance between two adjacent floors, two pairs of floor relays are provided for each car, one pair for operating the control relay when the car is to be decelerated from its normal high speed to a stop at a landing more than one floor away and the other pair for energizing the controller relay when the car is standing at one floor and is to make a stop at the next floor.

As shown, the control relay for the car A is 85 designated as Co. As a convenient reference, it may be stated that its contact members control circuits as follows:

a=Completes a self-holding circuit for the relay Co.

b=Energizes the inductor relay coils.

c=Restores the floor push buttons.

d=Restores the car push buttons.

e=Lights the down floor lanterns.

f=Lights the up floor lanterns.

g=Prevents the operation of the car at high speed when a one-floor run is to be made.

The floor relays associated with the car A are designated as follows:

R1=Is energized by the push buttons in car A when the car is to be decelerated from high speed to a stop at a floor.

R2=Is energized by the floor push buttons when the car is to be decelerated from high speed to a stop at a floor.

G1=Is energized by the push buttons in car A when a one-floor run is to be made.

G2=Is energized by the floor push buttons when a one-floor run is to be made.

The push buttons disposed in the car A to be operated by the car attendant when he desires to register or set up calls that will cause the car to stop at the floors where passengers desire to get off, are designated as A-2, A-3 and A-8.

Similar push buttons B-2, B-3 and B-8 are disposed in the car B to enable the attendant in that car to stop at any landing to discharge passengers.

The push buttons disposed at the floor landings to enable waiting passengers to register or set up calls that will cause the first car to approach in a corresponding direction to stop thereat so that they may board it are designated as follows:

The up and the down buttons for the second floor are respectively numbered 2-U and 2-D while those for the third and eighth floors are designated as 3-U and 3-D and 8-U and 8-D.

For the purpose of signalling a passenger waiting at a floor landing that a car approaching in the direction in which he desires to go will make a stop at his landing, each car is electrically connected to indicating devices, preferably electric lamps, which are mounted outside of the elevator shafts at the floor landings. Each of the top and bottom floors is provided with a single lamp or floor lantern for each car, while each of the intermediate floors is provided with a pair of lanterns for each car, one serving to indicate that the corresponding car is approaching in a downward direction and the other in an upward direction. The floor lanterns for the car A are designated as L-1, L-2D, L-2U, L-3D, L-3U, L-3D, L-8U and L-9.

The floor lanterns for the car B are designated as L-1', L-2D', L-2U', L-3D', L-3U', L-8D', L-8U' and L-9'.

In order that the various circuits for the push buttons, floor relays and floor lanterns may be

completed in accordance with the positions of the cars with respect to the associated floors, the car A is provided with a floor selector FS and the car B with a floor selector BFS. The floor selectors may be located at any suitable point, such, for example, as in the pent house or in the elevator shafts and, as illustrated, are similar to those usually employed in elevator systems.

10 As shown, the selector FS for the car A is provided with a set of up contact segments and a set of down contact segments that are disposed to be engaged by cooperating brushes 10 to 27, inclusive, mounted upon, and insulated from, a movable arm MA.

15 The movable arm MA is operated in accordance with the movements of the car A by means of a screw AS that is driven by some part of the operating mechanism of the car which the selector serves.

20 Usually, the frictional engagement between arm MA and its operating screw AS will cause the arm to bear upon the up contact segments when the car is travelling upwardly and upon the down contact segments when the car is travelling downwardly. However, in the present system, it is desirable to have the movable arm MA tilted to the opposite side as soon as the car reaches the limit of its up and down travel.

25 30 Therefore, the selector is provided with a pair of electromagnets 30 and 31 that may be energized to cause the arm MA to tilt in the proper direction upon reaching the end of its travel.

35 The electromagnets 30 and 31 may be energized to tilt the movable arm MA when the car reaches the limit of its up and down travel, by having the coils connected in circuit with, and controlled by, an "up" selector relay 32 and a "down" selector relay 33, which, in turn, are controlled by a pair of limit switches 34 and 35.

40 45 The group of "up" contact segments under the brushes 10, 11 and 12 control the lighting of the up floor lanterns to indicate to waiting passengers that the car will stop for them.

50 The group of "up" contact segments under the brushes 13, 14 and 15 connect the floor buttons, and the group of "up" contact segments under the brushes 16, 17 and 18 connect the car buttons, with the floor relays for stopping the car.

55 60 As shown, the brushes 10, 11 and 12 for the "up" floor-lantern segments are so disposed on the arm MA that the high-speed brush 10 will engage the floor-lantern segment for a floor when the car is two floors away from that floor, the intermediate-speed brush 11 will engage the segment when the car is one floor away and the brush 12 will be in engagement with the segment when the car is standing, thus providing means whereby an energized segment will keep a floor lantern lighted while a car decelerates from high speed to a stop at a floor and remains standing at that floor.

65 70 75 The express brush 13 for the "up" floor-button segments is so disposed on the arm MA that it will engage the floor-button segment for a floor when the car is approximately three floors from that floor. The express brush 13 is connected in the circuit for the coil of the express control relay 6. Therefore, when the express brush 13 comes into engagement with a contact segment that has been energized by the registration of a stop call, it will energize the relay 6 to open the circuit for the express relay 5.

Thus, if the car A approaches a registered call at express speed, the express brush 13 will come into engagement with the segment when the car is three floors away from the floor from which the stop call exists and will thereby cause the car to decelerate from its express speed to its normal-speed so that it will be running at such speed, when it picks up the registered stop call, that it will be stopped exactly level with the floor for which the registered stop call exists. 85

The brushes 14 and 15 for the up floor-button segments are disposed on the arm MA in such manner that the high-speed brush 14 will engage the floor-button segment for a floor when the car is approximately two floors away from that floor, and the standing brush 15 will be in engagement with the segment when the car is one floor away, thus providing separate circuits for operating the high-speed floor relay and the low-speed or standing floor relay associated with the car A. 90 95

The express brush 16, the high-speed brush 17 and the standing brush 18 for the "up" car button segments are disposed on the arm MA substantially as brushes 13, 14 and 15 are disposed for decelerating the car A when a car button in car A has been pressed to energize a car button segment to stop the car. 100

The "down" side of the selector comprises a duplicate of the "up" contact segments and brushes except for a reversal of their order and position. 105

As stated above, the controlling apparatus for the car B is similar, in all respects, to that described in connection with the car A, except that the contact segments on its floor selector BFS for the car B are connected by conductors 36, 37, 38, 65, 66 and 67 to the floor push buttons 2U, 2D, 3U, 3D and 8U and 8D instead of to a separate set of floor push buttons. Therefore the push buttons 2U, 2D, 3U, 3D and 8U and 8D are common to both the cars A and B and the pressing of any one button will energize the floor button contact segments of both cars to cause the first car to approach in a corresponding direction to stop at the floor at which the button has been pressed. 115 120

125 My invention may be best understood from an assumed operation of the apparatus represented in the drawings.

Assuming that the car B is standing at the upper landing; that the car A is standing at the first floor landing ready to start upwardly and that a passenger waiting at the second floor presses the "up" button 2U to register a stop call 130 that will cause a car to stop at the second floor, then the operation of the push button 2U closes a self-holding circuit for itself that extends from the supply conductor L1, through conductor 40, the contact members of button 2U, holding coil 131 and conductor 42, to supply conductor L2.

Inasmuch as the car A is standing at the floor below that floor at which the stop call exists, the pressing of the button 2U also completes a circuit for energizing the floor relay G2 to cause the car to stop at the second floor, which circuit extends from supply conductor L1, through conductor 40, the contact members of push button 2U, conductor 43, restoring coil 44, conductor 45, contact segment 46, brush 15, conductors 47 and 48, the contact members f of up-direction switch 1, conductor 49, the contact members f of down-direction switch 2, conductor 50, the coil of relay G2 and conductors 51 and 52, to line conductor L2. 135 140 145 150

The closing of the contact members on the floor relay G2 completes a circuit for energizing the control relay Co to thereby effect the restoration of the push button 2U, the lighting of the floor lantern L2U, and the energization of the inductor relays to stop the car at the second floor, which circuit extends from line conductor L1, through conductors 55 and 56, the contact members of stopping inductor relay S, conductors 57 and 58, the coil of relay Co, conductors 59 and 60, the contact members *a* of relay G2 and conductors 61, 62 and 52, to supply conductor L2.

The closing of the contact members *a* on the control relay Co completes a self-holding circuit for that relay which extends from the supply conductor L1, through conductor 55, as just described, to the coil of the relay Co and thence, through the contact members *a* thereof and conductors 63 and 64, to supply conductor L2.

The closing of the contact members *c* on the control relay Co completes a circuit for fully energizing the restoring coil 44 to restore the floor push button 2U to its open position, which circuit extends from the supply conductor L1, through conductor 40, the contact members of push button 2U, conductor 43, restoring coil 44, conductor 45, contact segment 46, brush 15, conductor 47, the contact members *e* of relay 4, conductor 53, the contact members *c* on relay Co, conductor 100, the contact members 101, 71 and 72 on the car switch CSA and conductors 73 and 42, to supply conductor L2.

The holding coil 41 and the restoring coil 44 on the push button 2U are wound in opposition to each other so as to oppose each other magnetically. Therefore, when the restoring coil 44 is fully energized, it has sufficient magnetic force to neutralize the magnetic force of the holding coil 41, thereby causing it to release the push button to its normal open position. Thus, the push button 2U will be restored to its open position to make it ready for future operation and to prevent the registered stop call from being picked up by any other car when full current is supplied to the restoring coil 44. When the restoring coil 44 was in series with the coil of the floor relay G2, during the energization of that relay, there was sufficient resistance in the coil of relay G2 to prevent the restoring coil 44 from being sufficiently energized to magnetically overcome the holding coil 41.

The floor relay G2 is deenergized when the contact members on the push button 2U are opened.

It should be noted here that the push button 2U is restored to its open position as soon as the relays G2 and Co operate, because the car A is at the next floor below, with its car switch CSA in a centered position. If no car were standing at the next floor below, the restoring coil 44 would not be fully energized until a car came to, and stopped at, the lower terminal. Hence, in the absence of a car at the lower terminal, the push button 2U would have remained in its depressed position until a car arrived, thus indicating to the waiting passenger at the second floor that the stop call was registered.

The opening of the contact members *g* on the control relay Co opens the circuit to the coil of the high-speed relay 4 and thereby prevents the car from running at high speed, so that it may make a one-floor run to the second floor.

Further explanation of the operation of the control relay Co will be deferred until the start-

ing of the car by the car attendant is described.

Assuming now that the attendant on the car A decides to make an up run, under our assumed condition of operation, he will start the car from the first floor in the usual manner by operating the car switch CSA in a clockwise direction to full-speed position and then returning it to its control position. In the control system illustrated in the drawings, the attendant will normally throw the car switch all the way over to its high-speed position, hold it there for a short period to permit the various relays to pick up and then recenter it, so that the car will be stopped at any floor by its inductor relays when they are energized as a result of the operation of the push buttons at the floor landings or in the car. If the car switch is held in its high-speed position, the inductor relays cannot be energized, and the car will run through its stop calls.

The movement of the car switch CSA in the clockwise direction completes a circuit for energizing the up-direction switch 1 to start the car upwardly, which circuit extends from supply conductor L1, through conductors 55 and 56, the contact members of inductor relay S, conductors 57 and 68, the coil of up-direction switch 1, conductor 69, the contact members 70, 71 and 72 of car switch CSA and conductors 73 and 42, to supply conductor L2.

The closing of the contact members *a* on the up-direction switch 1 completes a self-holding circuit for that switch which extends from supply conductor L1 to the coil of up-direction switch 1, as just described, and thence through conductor 74, the contact members *a* of up-direction switch 1 and conductors 75 and 76, to supply conductor L2.

The closing of the contact members *b* and *c* on the up-direction switch 1 energizes the field winding GF of the generator G with current in one direction by way of a circuit that extends from supply conductor L1, through conductors 77 and 78, the contact members *b* of up-direction switch 1, conductors 79 and 80, the field winding GF, conductors 81 and 82, the contact members *c* of up-direction switch 1, conductors 83 and 84, resistor sections *r*1, *r*2 and *r*3 and conductor 85, to supply conductor L2.

The energization of the field winding GF causes the generator G to supply current in one direction to the hoisting motor EM, and the car starts upwardly.

As the attendant continues the movement of the car switch CSA in a clockwise direction, a circuit is completed for energizing the intermediate-speed relay 3 for causing the car to operate at its intermediate speed, which circuit extends from supply conductor L1, through conductors 55, 56 and 87, the contact members of inductor relay SD, conductor 88, the contact members of inductor relay SU, conductor 89, the coil of high speed relay 3, conductors 90 and 91, the contact members 92, 71 and 72 of car switch CSA and conductors 73 and 42, to supply conductor L2.

The closing of the contact members *a* on the intermediate-speed relay 3 completes a self-holding circuit for that relay extending from supply conductor L1 to the coil of relay 3, as just described, and thence, through the contact members *a* of relay 3 and conductors 93 and 94, to supply conductor L2.

The closing of the contact members *b* on the intermediate-speed relay 3 shunts the resistor

section r_3 from the circuit previously traced for the field winding GF to thereby cause the car to travel at a higher speed.

The final movement of the car switch CSA to its high-speed position closes its contact members for the high-speed relay 4 but, inasmuch as the circuit for the relay 4 must be completed through the contact members g on the floor control relay Co, which are now open because that relay is energized, the car will not get into high speed and will operate only at its intermediate speed so that it may be stopped at the second floor by the inductor relays.

Assuming that the car attendant has re-centered the car switch CSA, we will again take up the operations effected by the energizing of the control relay Co.

The closing of the contact members b on the control relay Co completes a circuit for energizing the slow-down and stopping inductor relays HU, SU and S on the car A to stop the car at the second floor, which circuit extends from supply conductor L1, through conductors 55 and 56, the coil of stopping relay S, conductors 95 and 96, in parallel through the coils SU and HU, conductor 97, the contact members d of up-direction switch 1, conductors 98 and 99, the contact members b of relay Co, conductor 100, the contact members 101, 71 and 72 of car switch CSA and conductors 73 and 42, to supply conductor L2.

The energization of the inductor relays SU and S causes them to be actuated to open their contact members as they pass the inductor plates SU' and S' and thereby open the circuits for the intermediate-speed relay 3 and the up-direction switch 1, thus deenergizing the relay 3 and the up-direction switch 1 and bringing the car to a stop at the second floor.

The opening of the contact members on the inductor relay S also deenergizes the control relay Co and renders it ready to be again energized when the next stop is to be made.

When the control relay Co was energized, the closing of its contact members f completed a circuit for lighting the floor lantern L2U at the second floor for indicating to the waiting passenger at that floor that the car would stop thereat, which circuit extended from supply conductor L1, through conductors 55 and 105, lamp L2U, conductor 106, contact segment 107, brush 11, conductor 108, the contact members g of high-speed relay 4, conductor 109, the contact members d of intermediate speed relay 3, conductor 110, the contact members f of relay Co, conductor 100, contact members 101, 71 and 72 of car switch CSA and conductors 73 and 42, to supply conductor L2.

As the car A approached, and stopped at the second floor, the arm MA on the floor selector FS moved to such position that the standing brush 12 engaged the contact segment 107 and, therefore, the circuit for lighting the floor lantern L2U was transferred from the low-speed brush 11 to the standing brush 12, which circuit now extends from the supply conductor L1 to the contact segment 107, as just described, and thence, through the brush 12, conductor 111, the normally closed contact members e of intermediate-speed relay 3, conductor 100, the contact members 101, 71 and 72 of car switch CSA and conductors 73 and 42, to supply conductor L2.

Thus, the arrangement of the intermediate-speed brush 11 and the standing brush 12 caused

the floor lantern L2U to be lighted when the car A was at the first floor and to thereafter remain lighted while the car ran to, and stopped at, the second floor. The floor lantern will stay lighted while the car remains at the second floor, but will be extinguished when the contact members 101 and 72 on the car switch CSA are separated by the operation of that switch to start the car.

Assuming now that the waiting passenger at the second floor has boarded the car and that the attendant again starts the car upwardly by moving the car switch CSA in a clockwise direction to its full-speed position, then the up-direction switch 1 and the intermediate-speed relay 3 will be energized for operating the car upwardly at intermediate speed, as previously described.

Inasmuch as no stop call is registered or exists for the next floor, the contact members g on the control relay Co are closed. Therefore, when the car switch is moved to full-speed position, a circuit will also be completed for energizing the high-speed relay 4 to operate the car at high speed, which circuit extends from supply conductor L1, through conductors 55, 56 and 115, the contact members of inductor relay HD, conductor 116, the contact members of inductor relay HU, conductor 117, the coil of high-speed relay 4, conductor 118, the contact members a of voltage relay 7, conductor 119, the contact members g of control relay Co, conductor 120, contact members 121, 71 and 72 of the car switch CSA and conductors 73 and 42, to supply conductor L2.

The closing of the contact members a on the high-speed relay 4 completes a holding circuit for that relay extending from supply conductor L1 to the coil of relay 4, as just described, and thence, through conductor 125, the contact members a of relay 4, conductors 126, 93 and 94, to supply conductor L2.

The closing of the contact members b on the high-speed relay 4 serves to shunt the resistor section r_2 from the circuit previously traced for the field winding GF to thereby cause the car to travel at high speed.

Assuming now that the "dispatcher" in charge of the elevator system closes the express-speed switch 9 to speed up the operation of the car A so that it will return to the terminal as soon as possible, then the express relay 5 will be energized to operate the car at its express speed by way of a circuit that extends from supply conductor L1, through conductor 55, the dispatching switch 9, conductor 127, the coil of relay 5, conductor 128, the contact members a of relay 6, conductor 129, the contact members b of voltage relay 7 and conductor 94, to supply conductor L2.

The closing of the contact members on the express relay 5 serves to shunt the resistor section r_1 from the circuit previously traced for the field winding GF, thereby allowing full line voltage to be supplied to the winding GF to cause the car to travel at full express speed.

Assuming now that a passenger waiting at the eighth floor landing pressed the up button 8U as the car A left the first floor to answer the second floor call and thereby registered a stop call for stopping a car at the eighth floor, then the pressing of the button 8U energized the holding coil 130 for maintaining the button 8U in a depressed position by way of a circuit that extends from supply conductor L1, through conductor 131, the contact members of button 8U,

the holding coil 130 and conductor 42, to supply conductor L2.

The energization of the holding coil 130 will maintain the button 8U in its depressed position 5 to indicate to waiting passengers at the eighth floor that the button has been operated and that an up stop call at the eighth floor is registered.

The maintenance of the button 8U in its 10 pressed condition will also cause current to be supplied to the contact segment 132 on the floor selector FS and to the contact segment 124 on the floor selector BFS for energizing the high-speed floor relay R2 for the first car to approach the eighth floor in the up direction in order to stop that car at the eighth floor. However, as before stated, car B is at the top landing and car A is moving upwardly. Therefore, car A will be the first car to approach the registered call at the eighth floor and it will be stopped at that floor. As the car A approaches the eighth floor stop at express speed, the movable arm MA on the floor selector FS will cause the express brush 13 to engage the energized 25 contact segment 132 in advance and thereby energize the express control relay 6 to decelerate the car from its express speed to its high speed by way of a circuit which extends from supply conductor L1, through conductor 131, the 30 contact members of floor button 8U, restoring coil 133, conductor 134, contact segment 132, brush 13, conductor 135, the coil of relay 6, and conductors 136 and 85, to supply conductor L2.

The closing of the contact members b of the 35 relay 6 completes a self-holding circuit for that relay which extends from supply conductor L1, through conductors 55 and 56, the contact members of inductor relay S, conductors 57 and 140, the contact members b of relay 6, conductor 40 141, the coil of relay 6 and conductors 136 and 85, to supply conductor L2.

The opening of the normally closed contact members a on the relay 6 deenergizes the express relay 5, which causes the contact members 45 a of relay 5 to open and thus reinser the resistor section r1 in the circuit for the field winding GF of the generator G to thereby slow down the car A to its normal high speed.

As the car A continues its approach to the 50 eighth floor, the floor selector arm MA causes the high-speed brush 14 to engage the energized contact segment 132 and thereby complete a circuit for energizing the floor relay R2 to stop the car A at the eighth floor, which circuit extends from supply conductor L1, through conductor 55 and 56, the contact members of floor button 8U, the restoring coil 133, conductor 134, contact segment 132, brush 14, conductor 142, the coil of relay R2 and conductors 143 and 64, to supply conductor L2.

The closing of the contact members of the floor relay R2 completes a circuit for energizing the control relay Co, which circuit extends from the supply conductor L1, through conductors 55 and 56, the contact members of inductor relay S, conductors 57 and 58, the coil of relay Co, conductor 59, the contact members of relay R2 and conductors 144, 145 and 64, to supply conductor L2.

The closing of the contact members a of the 70 relay Co completes a self-holding circuit for that relay extending from supply conductor L1 to the coil of relay Co, as just described, and then, through the contact members a of relay Co and 75 conductors 63 and 64, to supply conductor L2.

The closing of the contact members b on the control relay Co completes a circuit for energizing the inductor relays HU, SU and S on the car A for stopping the car at the eighth floor, as previously described.

As the car passes the eighth floor inductor plate HU', the energized inductor relay HU will be actuated to open its contact members and thereby open the holding circuit for the high-speed relay 4 to automatically slow down the car to intermediate speed.

As the car continues toward the eighth-floor level, the energized inductor relay SU passes the eighth-floor inductor plate SU' and is actuated to open its contact members to deenergize the intermediate-speed relay 3 for automatically bringing the car to a still lower speed as it approaches the point at which the power should be shut off.

As the car continues toward the eighth-floor level, the energized stopping inductor relay S passes the inductor plate S' and is actuated thereby to open the circuit to the up-direction switch 1 for deenergizing the generator winding GF and bringing the car to a stop at the eighth floor. The opening of the contact members on the inductor relay S also deenergizes the control relay Co.

The opening of the contact members on the stop inductor relay S also deenergizes the holding circuit for the express control relay 6, thereby restoring that relay to its normal condition in which its contact members a are closed to permit the express relay 5 to be again energized.

When the control relay Co was energized as 115 the car approached the eighth floor, the closing of its contact members c restored the push button 8U to its normal open position by completing a circuit in shunt with the floor relay R2 to permit full current to be applied to the restoring coil 133 and cause it to overcome the holding coil 130, which circuit extends from supply conductor L1, through conductor 131, the contact members of push button 8U, restoring coil 133, conductor 134, contact segment 132, brush 14, conductors 142 and 137, the contact members f of relay 4, conductor 53, the contact members c of relay Co, conductor 100, the contact members 101, 71 and 72 of car switch CSA and conductors 73 and 42, to supply conductor L2.

The opening of the contact members on the restored push button 8U opened the circuit for the energized floor relay R2 and restored that relay to its deenergized condition.

At the same time, the closing of the contact members f on the control relay Co completed a circuit for lighting the up-floor lamp L8U at the eighth floor to indicate to waiting passengers at that floor that the car A would stop thereat, which circuit extends from supply conductor L1, through conductors 55 and 105, the lamp L8U, conductor 146, contact segment 149, brush 10, conductor 150, the contact member h of high-speed relay 4, conductor 109, the contact members d of relay 3, conductor 110, the contact member f of relay Co, conductor 100, the contact members 101, 71 and 72 of car switch CSA and conductors 73 and 42, to supply conductor L2.

As the car continues toward the eighth-floor stop, the arm MA moves along the floor selector until the intermediate-speed brush 11 engages the contact segment 149, thereby causing the circuit for lighting of the floor lantern LHU to be transferred from brush 10 to brush 11, which 115

circuit now extends from supply conductor L1 to the contact segment 149, as just described, and then, through brush 11, conductor 108, the normally closed contact members *g* of relay 4, conductor 109, the contact members *d* of relay 3, conductor 110, the contact members *f* of relay Co, conductor 100, the contact members 101, 71, and 72 of car switch CSA and conductors 73 and 42, to supply conductor L2.

10 As the car comes to rest at the eighth-floor landing, the arm MA on the floor selector FS moves to such position that the standing brush 12 is disposed on the contact segment 149.

15 Therefore, the circuit for lighting the floor lantern L8U is transferred from intermediate-speed brush 11 to the standing brush 12, which circuit now extends from the supply conductor L1 to the contact segment 149, as previously described, and then, through brush 12, conductor

20 111, the contact members *e* of relay 3, conductor 100, the contact members 101, 71 and 72 of car switch CSA and conductors 73 and 42, to supply conductor L2.

25 Thus, the arrangement of the high-speed switch 10, the intermediate-speed brush 11, and the standing brush 12 causes the floor lantern L8U to be lighted when the car A begins to make the stop at the eighth floor, that is, comes into the stopping zone for the eighth floor and to 30 thereafter remain lighted while the car slows down and while it stops at that floor. The floor lantern L8U will be extinguished by the separation of the contact members 101 and 72 on the car switch CSA when the switch moved to start 35 the car.

Assume now that the car A completes its stop at the eighth floor and that the attendant again moves the car switch CSA in a clockwise direction, then the up-direction switch 1 will be 40 energized, as previously described, and the car will start and move to the upper terminal floor.

As the car A arrives at the end of its up run and is brought to a stop by the usual terminal switches (not shown), the cam member 151 on 45 the upper left-hand corner of the car A opens the limit switch 34 to deenergize the up selector relay 32 and energize the down selector relay 33 for causing the movable arm MA to be tilted over so that it bears upon the down contact segment on the floor selector FS.

50 The circuit, completed by the closing of the contact members *a* on the selector relay 32 for energizing the selector relay 33, extends from supply conductor L1, through conductor 152, the coil of relay 33, conductor 154, the contact members *a* of relay 32, conductor 155, the contact members of limit switch 35 and conductors 156 and 42, to supply conductor L2.

55 The opening of the normally closed contact members *a* on the relay 33 prevents reenergization of the relay 32 until the relay 33 is again deenergized when the car reaches the lower terminal.

60 The closing of the contact members *b* on the relay 33 completes a circuit for energizing the electro-magnet 31 to tilt the arm MA until it rests upon the down contact segments, which circuit extends from supply conductor L1, through conductors 152, 157, and 158, the contact members *b* on relay 33, conductor 159, the coil of electromagnet 31 and conductors 160 and 162 to supply conductor L2.

65 Assuming now that the car A has taken on a number of passengers at the upper terminal and 70 is ready to start down and that the car attend-

ant moves the car switch CSA in a counter-clockwise direction, then a circuit is completed for energizing the down-direction switch 2 to start the car downwardly, which circuit extends from supply conductor L1, through conductors 55 and 56, the contact members of stopping inductor relay S, conductors 57 and 165, the coil of relay 2, conductors 166 and 167, the contact members 168, 71 and 169 on the car switch CSA and conductors 73 and 42, to supply conductor L2.

75 The closing of the contact member *a* on the down-direction switch 2 completes a self-holding circuit for that switch, extending from supply conductor L1, through the coil of down-direction switch 2, as just described, and thence, through conductor 166, the contact members *a* of direction switch 2 and conductors 170 and 76, to supply conductor L2.

80 The closing of the contact members *b* and *c* on the down-direction switch 2 energizes the field winding GF of the generator G with current in the reverse direction by way of a circuit that extends from supply conductor L1, through conductors 77, 78, and 175, the contact members *b* on down-direction switch 2, conductor 81, the winding GF, conductors 80 and 176, the contact members *c* of down-direction switch 2, conductors 177 and 83, the resistor sections *r*1, *r*2, and *r*3 and conductor 85, to supply line L2.

85 The energization of the field winding GF causes the generator G to supply current in the reverse direction to the hoisting motor EM, and the car starts downward.

90 As the attendant continues the movement of the car switch CSA in a counter-clockwise direction, a circuit is completed for energizing the intermediate-speed relay 3 to cause the car to operate at its intermediate speed, which circuit 95 extends from supply conductor L1, through conductors 55 and 56, the contact members of inductor relay SD, conductor 88, the contact members of inductor relay SU, conductor 89, the coil of relay 3, conductor 90, contact members 180, 71, and 169 of car switch CSA and conductors 73 and 42, to supply conductor L2.

100 The closing of the contact member *a* on the intermediate-speed relay 3 completes a self-holding circuit for that relay which extends 105 from supply conductor L1 to the coil of relay 3, as just described, and thence, through the contact members *a* of relay 3 and conductors 93 and 94, to supply conductor L2.

105 The closing of the contact members *b* on the intermediate-speed relay 3 shunts the resistor section *r*3 from the circuit of the field winding GF, as just described, thereby causing the car A to travel at its intermediate speed.

110 Assuming that the attendant desires to cause the car to travel at a still greater speed, he moves the car switch CSA further in its counter-clockwise direction, then a circuit for energizing the high-speed relay 4 to cause the car to travel at its high speed will be completed from supply conductor L1, through conductors 55, 56 and 115, the contact members of inductor relay HD, conductor 116, the contact member of inductor relay HU, conductor 117, the coil of high speed relay 4, conductor 118, the contact members *a* of voltage relay 7, the conductor 119, the contact members *g* of the control relay Co, conductors 120 and 181, the contact members 182, 71 and 169 of car switch CSA and conductors 73 and 42, to supply conductor L2.

The closing of the contact members *a* on the high-speed relay 4 completes a self-holding circuit for that relay extending from supply conductor L1 to the coil of the relay 4, as just described, and thence, through conductor 125, the contact members *a* of relay 4 and conductors 126, 93 and 94, to supply conductor L2.

The closing of the contact member *b* on the high-speed relay 4 shunts the resistor section 72 from the circuit of the field winding GF, as previously described, thereby causing the car to travel at an increased speed.

Inasmuch as the "dispatcher" has not yet opened the express-speed switch 9, the car is still conditioned to operate at express speed. Therefore, as soon as the generator G reaches a predetermined speed, the voltage relay 7 will close its contact members *b* to complete the hereinbefore described circuit for energizing the express speed relay 5. Consequently, that relay closes its contact members, thereby shunting the resistor section 71 from the circuit of the field winding GF, as previously described, and causing the car to travel downwardly at express speed.

Assuming further that some of the passengers taken on at the upper terminal called out stops for the third and second floors and that the attendant pressed the push buttons A3 and A2 to register the stops indicated by the passengers so that the car will be automatically stopped at those floors, then circuits have been partially prepared for energizing the floor relays R1 and G1 to effect the stopping of the car at the third and second floors, which circuits will be completed when the car enters the decelerating zones for the landings and causes the brushes and contact segments on the floor selector to complete the prepared circuits.

The pressing of the button A3 completed a self-holding circuit for that button extending from supply conductor L1, through conductors 55, 185 and 186, the contact members of button A3, holding coil 187 and conductors 188 and 42, to supply conductor L2. The closed condition of the button A3 supplies energy to the contact segment 190 on the floor selector for stopping the car and, at the same time, indicates to the car attendant that a call has been registered to stop the car at the third floor.

As the car A approaches, at express speed, the down stop at the third floor, it will be decelerated from the express speed to its low speed because the arm MA on the floor selector will cause the express brush 21 to engage the energized contact segment 190 and thereby energize the express control relay 6 by way of a circuit which extends from supply conductor L1, through conductors 55, 185, 186, the contact members of push button A3, conductor 191, restoring coil 192, conductor 193, contact segment 190, brush 21, conductors 194 and 135, the coil of express control relay 6 and conductors 136 and 85, to supply conductor L2.

The closing of the contact members *b* on the relay 6 completes a self-holding circuit for that relay, as hereinbefore described.

The opening of the normally closed contact members *a* on the relay 6 deenergizes express relay 5 and causes the car A to decelerate from express speed to its high speed.

As the car A continued its approach to the down stop at the third floor, the high-speed brush 20 engages the energized contact segment 190 on the floor selector, and thereby completes

the circuit partially prepared by the operation of the push button A3 for operating the floor relay R1 to effect the stopping of the car at the third floor, which circuit extends from supply conductor L1, through conductors 55, 185 and 186, the contact members of push button A3, conductor 191, restoring coil 192, conductor 193, contact segment 190, brush 20, conductors 195, 196, the coil of floor relay R1 and conductors 197 and 64, to the supply conductor L2.

The closing of the contact members on the floor relay R1 completes a circuit for energizing the control relay Co, which circuit extends from supply conductor L1 through conductors 55 and 56, the contact members of inductor relay S, conductors 57 and 58, the coil of relay Co, conductor 59, the contact members of relay R1 and conductors 198, 145 and 64, to supply conductor L2.

The closing of the contact members *a* on relay Co completes a self-holding circuit for that relay which extends from the supply conductor L1 to the coil of relay Co, as just described, and thence, through the contact members *a* of relay Co and conductors 63 and 64, to supply conductor L2.

The closing of the contact members *b* on the relay Co completes a circuit for energizing the inductor relays HD, SD, and S, so that they will be actuated by the inductor plates HD', SD' and S' to bring the car to a stop at the third floor landing, which circuit extends from supply conductor L1, through conductors 55 and 56, the coil of inductor relay S, conductors 95 and 200, in parallel through the inductors HD and SD and thence through conductor 201, the contact members *d* of down-direction switch 2 and conductor 99, the contact members *b* of relay Co, conductor 100, the contact members 101, 71, and 169 of car switch CSA and conductors 73 and 42, to supply conductor L2.

The energization of the inductor relays HD, SD and S by the operation of the control relay Co closing its contact member *b*, causes the inductor relays to be actuated to open their contact members as they pass the inductor plates HD', SD', and S' for the third floor and thereby open the circuits for high-speed relay 4, intermediate-speed relay 3 and the down-direction switch 2, thus deenergizing the high-speed relay 4, the intermediate speed relay 3, and down-direction switch 2, and bringing the car to a stop at the third floor.

At the time the control relay Co was energized, it closed its contact members *d* to complete a circuit for causing the car button A3 to be restored to its normal open position, which circuit extends from supply conductor L1, through conductors 55, 185 and 186, the contact members of button A3, conductor 191, restoring coil 192, conductor 193, contact segment 190, high-speed brush 20, conductors 195, 196 and 202, the contact members *d* of relay 4, conductor 203, the contact members *d* of relay Co, conductor 100, contact members 101, 71 and 169 of car switch CSA and conductors 73 and 42, to supply conductor L2.

It will be noted that this circuit is a shunt circuit around the coil of the floor relay R1. Therefore, full voltage is supplied to the restoring coil 192 and it overcomes the holding coil 187, thus restoring the push button A3 to its normal open position. The opening of the contact members of the push button A3 deenergizes the floor relay R1 and restores it.

At the same time, the energization of the control relay Co closed its contact members e which completed a circuit for lighting the down floor lantern L3D at the third floor to indicate to waiting passengers that the car A would stop at that floor, which circuit extends from supply conductor L1, through conductors 55 and 105, floor lantern L3D, conductor 204, contact segment 205, brush 27, conductor 206, the contact member J of high-speed relay 4, conductor 207, the contact members f of relay 3, conductor 208, the contact members e of relay Co, conductor 100, the contact members 169, 71 and 101 of car switch CSA and conductors 73 and 42, to supply conductor L2.

As the car continues toward the third floor, the floor selector arm MA moves downwardly until the low-speed brush 26 engages the contact segment 205 and thereby causes the lighting 20 of the floor lantern L3D to be transferred from brush 27 to brush 26 by way of a circuit that extends from the supply conductor L1 to the contact segment 205, as just described, and then, through brush 26, conductor 209, the normally closed contact members i of high-speed relay 4, conductor 207, the contact members f of intermediate-speed relay 3, conductor 208, the contact members e of relay Co, conductor 100, contact members 101, 71 and 169 of car switch CSA and 30 conductors 73 and 42, to supply conductor L2.

As the car comes to rest at the third floor landing, the arm MA on the floor selector moves to such position that the standing brush 25 is disposed on the contact segment 205, thus transferring the circuit for lighting the floor lantern L3D from the low-speed brush 26 to the standing brush 25, which circuit now extends from the supply conductor L1 to the contact segment 205, as just described, and then, through brush 25, conductor 210, the normally closed contact members c of relay 3, conductor 100, the contact members 101, 71 and 169 of car switch CSA and conductors 73 and 42, to supply conductor L2.

Thus, the arrangement of the high-speed brush 27, the intermediate-speed brush 26 and the standing brush 25 causes the down floor lantern L3D to be lighted when the car A prepares to stop at the third floor and to thereafter remain lighted while the car slows down, and 50 while it stops at that floor.

Assuming now that the stop at the third floor is completed, and, recalling that the car attendant pressed the car button A2 to cause the car to stop at the second floor on its down trip, then 55 the pressing of the button A2 completed a self-holding circuit for that button extending from supply conductor L1, through conductors 55, 185 and 212, the contact members of button A2, holding coil 213 and conductors 188 and 42, to supply conductor L2.

Inasmuch as the button A2 has been operated for a down stop at the second floor, the standing of the car at the third floor will cause a circuit to be completed for energizing the floor relay G1 to cause the car to stop at the second floor, which circuit extends from supply conductor L1, through conductors 55, 185 and 212, the contact members of button A2, conductor 225, restoring coil 214, conductor 215, contact segment 216, brush 19, conductors 217, 218 and 219, the contact members e of up-direction switch 1, conductor 220, the contact members e of down-direction switch 2, conductor 221, the coil of floor relay G1 and conductors 222 and 52, to supply 75 conductor L2.

The closing of the contact members on the floor relay G1 completes a circuit for energizing the control relay Co, which circuit extends from supply conductor L1, through conductors 55 and 56, the contact members of stopping conductor relay S, conductors 57 and 58, the coil of relay Co, conductors 59 and 60, the contact members of relay G1 and conductors 223, 62 and 52, to supply conductor L2.

The closing of the contact members a on the control relay Co completes a self-holding circuit for that relay which extends, as just described, from the supply conductor L1 to the coil of relay Co, and thence, through the contact members a of relay Co and conductors 63 and 64, to supply 85 conductor L2.

The closing of the contact members d on the relay Co completes a circuit for supplying full voltage to the restoring coil 214 to cause it to overcome the holding coil 213 and release the 95 push button A2 to its open position, which circuit extends from supply conductor L1, through conductors 55, 185 and 212, the contact members of button A2, conductor 225, restoring coil 214, conductor 215, contact segment 216, brush 19, 100 conductors 217 and 218, the contact members c of high-speed relay 4, conductor 203, the contact members d of relay Co, conductor 100, the contact members 101, 71 and 169 of car switch CSA and conductors 73 and 42, to supply conductor 105 L2.

The movement of the push button A2 to its open position, opens its contact members, thereby deenergizing the floor relay G1.

The closing of the contact members e on the 110 control relay Co completes a circuit for lighting the down floor lantern L2D, in a manner previously described.

The closing of the contact members b on the control relay Co completes a circuit for energizing the inductor relays, as previously described.

The opening of the contact members g on the control relay Co opens the circuit for the high-speed relay 4 and prevents the operation of the car at high speed, thus providing a means whereby the car A will run at intermediate speed upon being started from the third floor and make a one-floor run to the stop at the second floor.

Assuming now that the car attendant operates the car switch CSA in a counter-clockwise direction to its full running position in the usual manner after the stop at the third floor is completed, then the down-direction switch 2 and the intermediate speed relay 3 will be energized as previously described, and the car will make a one-floor run to and stop at the second floor. After the stop at the second floor is completed, the operation of the car may be continued here-tofore as described.

Thus, it will be seen that I have provided an elevator-control system that serves to indicate the registered condition of the control push buttons associated therewith, and which provides for restoring the push buttons to their normal open position as soon as the elevator car begins to answer a stop call set up by the buttons. It will also be noted that my control system requires a small number of parts and a minimum amount of wiring, as compared with the usual elevator-control systems.

While I have illustrated and described only one specific embodiment of my invention, I realize that it is susceptible of many modifications, therefore, I do not desire to be limited to the precise construction and arrangement of parts 130

illustrated and described, except as defined in the appended claims.

I claim as my invention:

6. In a control system for an elevator car operable past a landing, means for stopping the car at said landing, a control circuit for connecting said stopping means to a source of power, a push-button switch for partially closing said control circuit, a holding coil for maintaining said switch in a closed position, a circuit disposed to be completed by the closing of said switch for energizing said holding coil, means operably responsive to movement of the car for completing the closure of said control circuit, and means operably responsive to the operation of said stopping means for causing said holding coil to release said switch.
2. In a control system for an elevator car operable past a landing, means for stopping the car at said landing, a control circuit for connecting said stopping means to a source of power, a push-button switch for partially closing said control circuit, a holding coil for maintaining said switch in a closed position pending complete closure of said control circuit, a circuit disposed to be completed by the closing of said switch for energizing said holding coil, means operably responsive to movement of the car for completing the closure of said control circuit, a restoring coil for causing said holding coil to release said switch and means operably responsive to operation of said stopping means for energizing said restoring coil.
3. In a control system for an elevator car operable past a landing, means for stopping the car at said landing, a control circuit for connecting said stopping means to a source of power, a push-button switch for partially closing said control circuit, a holding coil for maintaining said switch in a closed position pending complete closure of said control circuit, a circuit disposed to be completed by the closing of said switch for energizing said holding coil, means operably responsive to movement of the car for completing the closure of said control circuit, a restoring coil associated with, and wound in opposition to, said holding coil for causing said holding coil to release said switch, and means operably responsive to operation of said stopping means for energizing said restoring coil.
4. In a control system for an elevator car operable past a landing, means for stopping the car at said landing, a control circuit for connecting said stopping means to a source of power, a push-button switch for partially closing said control circuit, a holding coil for maintaining said switch in a closed position pending complete closure of said control circuit, a circuit disposed to be completed by the closing of said switch for energizing said holding coil, means operably responsive to movement of the car for completing the closure of said control circuit, a restoring coil disposed in series with said stopping means in said control circuit, a secondary circuit disposed in shunt relation to said control circuit, and means for closing said secondary circuit to shunt said stopping means and thereby energize said restoring coil sufficiently to cause said holding coil to release said switch.
5. In a control system for an elevator car operable past a landing, means for stopping the car at said landing, a control circuit for connecting said stopping means to a source of power, a push-button switch for partially closing said control circuit, a holding coil for maintain-

ing said switch in a closed position pending complete closure of said control circuit, a circuit disposed to be completed by the closing of said switch for energizing said holding coil, means operably responsive to movement of the car for completing the closure of said control circuit, a restoring coil disposed in series with said stopping means in said control circuit, a secondary circuit disposed in shunt relation to said stopping means, and means operably responsive to the operation of said stopping means for closing said secondary circuit to shunt said stopping means and thereby energize said restoring coil sufficiently to cause said holding coil to release said switch.

6. In a control system for an elevator car operable past a landing, means for stopping the car at said landing, a control circuit for connecting said stopping means to a source of power, a push-button switch for partially closing said control circuit, a holding coil for maintaining said switch in a closed position pending complete closure of said control circuit, a circuit disposed to be completed by the closing of said switch for energizing said holding coil, means operably responsive to movement of the car for completing the closure of said control circuit, a restoring coil wound in opposition to said holding coil and disposed in series with said stopping means in said control circuit, a secondary circuit disposed in shunt relation to said stopping means, and means operably responsive to operation of said car-stopping means to stop said car for closing said secondary circuit to shunt said stopping means and thereby energize the restoring coil sufficiently to cause said holding coil to release said switch.

7. In a control system for an elevator car operable past a landing, means under the control of an attendant on said car for starting said car, means for stopping the car at said landing, a control circuit for connecting said stopping means to a source of power, a push-button switch for partially closing said control circuit, a holding coil for maintaining said switch in a closed position pending complete closure of said control circuit, a circuit disposed to be completed by the closing of said switch for energizing said holding coil, means operably responsive to movement of the car for completing the closure of said control circuit, a restoring coil in opposition to said releasing coil and in series with said stopping means in said control circuit, a shunt circuit around said stopping means, and means operably responsive to operation of said stopping means for completing said shunt circuit, said restoring coil to be so proportioned with reference to said holding coil as to remain ineffective while in series with the stopping means and to overcome the holding coil and cause it to release said switch when the shunt circuit is completed.

8. In a control system for a plurality of elevator cars operable past a landing, means associated with each car for stopping that car at said landing, a control circuit for connecting the stopping means for each car to a source of power, a push-button switch for partially closing said control circuit, a holding coil for maintaining said switch in a closed position, a circuit disposed to be completed by the closing of said switch for energizing said holding coil, means associated with each car and operably responsive to its movement for completing said control circuit to energize the stopping means on that car, and

- means operably responsive to the operation of the stopping means on the first car to stop at said landing in response to the operation of said push-button switch, for causing said holding coil to release said switch. 5
9. A control system for an elevator car comprising stopping switch mechanism, contactors controllable manually, oppositely wound windings operatively associated with said contactors, one to maintain them in actuated position and the other to neutralize the action of the maintaining winding to return said contactors to normal position, an energizing circuit for said other winding comprising contactors controllable by the car and additional contactors in series therewith, closed only after actuation of said stopping switch mechanism to render said other winding effective. 10
10. A control system for an elevator car comprising contactors for each of a plurality of landings controllable manually therefrom, oppositely wound windings operatively associated with the contactors for each of said landings, one of which maintains its contactors in actuated position, and the other of which is provided with a circuit controllable by the car and is effective when energized to neutralize the action of the 15

- means maintaining winding to cause its contactors to return to normal position. 11. A control system for an elevator car comprising up and down floor switches for each of a plurality of landings, each having oppositely wound windings, one of the windings of any of said switches energizable at any time regardless of the position of the car and the direction of movement of the car, and means to successively energize the other windings of said up switches when the direction of car movement is upwardly but not when it is downwardly, and means to successively energize the other windings of said down switches when the direction of car movement is downwardly but not when it is upwardly. 80
